UNITED STATES PATENT OFFICE.

RUDOLPH WELCKER, OF SPRINGFIELD, MASSACHUSETTS, ASSIGNOR OF ONE-FOURTH
TO FRANKLIN G. NEAL, OF SPRINGFIELD, MASSACHUSETTS.

TANK CAR.

Application filed April 28, 1924. Serial No. 709,627.

This invention is an improvement in tank car construction. Its general object is to provide an improved means for retaining liquids in tank cars, and for discharging them.

In the drawings:

Fig. 1 is a transverse sectional view through a railroad tank car showing in merely skeleton form the wheels of the car, its frame, the tank thereon with its dome, and the preferred relative position to these parts of the improved structure.

Fig. 2 is a vertical section with parts broken away, of the improved structure disclosing its details as it extends upwardly from the bottom of the tank.

Fig. 3 is a detail sectional view at the outlet point in the bottom of the tank showing a slight modification.

Fig. 4 is a detail of a slight modification. The dotted line through Figs. 1 and 2 indicates a normal level of liquid in the tank. According to my invention, I locate the outlet valve for the tank above the normal liquid level. Then by suitable means co-ordinated with the conditions of the valve and tank, I am able to take the liquid through said elevated valve when desired. The numerous advantages of the structure will appear as the description proceeds.

Pipe section 2 is fastened in a bottom opening of the tank. The vertical pipe section 8 has an annular valve part 9 on the bottom and valve part 12 on the top. Part 9 is normally seated in the inlet opening of pipe section 2 on a valve seat. It is not lifted from its seat except under special conditions such as when the tank is being cleaned, as will be described.

The part 12 has a valve seat to receive valve 11 which is fast on the upper end of tube 7. The latter is guided for vertical movement in one or more sleeves 10 supported by spiders from the inside of pipe section 8. The valve is normally held closed by the spring 13 between the sleeve 9 and a sleeve 14 fastened to the end of pipe 7. To open the valve, the pipe section 4 is elevated when turned for its threads to lift it by their engagement with threads in the packing box 15 in the bottom of pipe section 2, which elevation of pipe section 4 causes it to seat its upper end in the bottom of sleeve 14 and then lift pipe section 7 against spring

13. A hose connection 16 fast on the bottom of pipe 4 has a flange with a hole engageable by a removable handle 6 for the turning operation described to lift or lower pipe 4.

A ball check valve 18 is in the upper end of pipe 7 and a cap 17 to retain the ball in the pipe is on the end of said pipe. This cap has a sufficient skeleton flange to extend over the opening of pipe 7 as indicated to retain the ball. Another flange at the bottom of the cap 17 supports a spring whose upper end rests against a flange of the valve part 19. The latter has a central opening communicating with pipe 7 and the opening C which leads to the space A within the tank. The valve part 19 is a hollow shell like affair with a slidable support in a recess of valve 11 and with a flange overlying the top of valve 11 all as shown.

The upper end of this cylinder 24 is guided with a tight fit on a depending flange of the casting 27, is provided with threads to take the sleeve 26, (which sleeve is supported from the sides of the tank) between which and the casting 27 bolts may hold the said cylinder in any adjusted position with its bottom properly spaced from the bottom of the tank.

The operation in unloading a tank of oil includes the following steps, starting with the parts in the position shown. The handle 6 is turned to elevate pipe 4 which elevates pipe 7 and lifts valve 11. If the outlet 3 is closed (by any means not shown) until valve 19 seats on valve part 20 and then outlet 3 is opened (while pipe 5 is closed), atmospheric pressure will obtain in chamber B, but not in A. If the oil vapor over the liquid in the tank in chamber A is slightly above atmospheric pressure, as is usual in tank cars filled with oil, then the difference in pressure between chambers A and B will cause the liquid within the hanging cylinder 24 to rise, fill chamber B and flow down pipe 8. As soon as it is started, a siphon effect will continue it. The pipe 5 is open to the atmosphere so that when the pressure in chamber A becomes less than atmospheric pressure the ball check valve in pipe conduit 5, 7, and C will open, while the siphon works.

Suppose the original pressure above the liquid in chamber A is insufficient to start

the siphon effect. In such case, an air connection is made at 16 (which may be with the air brake line of the car or otherwise). With valve 11 elevated and valve 19 spaced 5 from its seat, the air rushes up pipe 7, is directed into the conduit C, and passes to the chamber A which is the space above the liquid in the tank 1. This action causes a partial vacuum in chamber B (because the 10 rush of air from pipe 7 to conduit C will draw air out of B) and an increased pressure in chamber A. The liquid will quickly rise in chamber B to flow into pipe 8 and the siphon effect is established. The air current 15 may then be turned off.

When very heavy liquids are to be taken from the tank, the air pressure may be maintained through pipe 7 to force the liquid up cylinder 24 and out pipe 8.

20 Instead of elevating the pipe section 4 by the means shown in Fig. 1, that shown in Fig. 4 may be used. In this modification pipe 4 slides through the packing box 15'. It is quickly lifted and lowered by the cam 25 and operating lever 6'. Therefore, valve 19 may be lifted to its seat quickly enough to avoid any substantial release of pressure which may be above the liquid in the tank, which would occur if the action is slow. A 30 valve in the upper end of pipe section 7 would then be closed, and it would not be necessary to close pipe 3 as when the valve 19 is lifted as suggested in connection with the parts shown in Fig. 2.

35 During any of the operations described, the workman does not need to open the dome of the tank car. These cars are always provided with a safety valve to prevent too high vapor pressure in the tank. It is 40 usually necessary for the workman to open the dome of a tank car and from it operate a mechanism in the dome (usually a vertical shaft with a connection to a valve in the bottom of the tank) to control the tank car 45 valve. This opening of the dome before emptying the tank has been the cause of many accidents to workmen. With my improved construction, the workman opens the valve above the liquid by a special tool or 50 handle 6 applied to pipe 5 under the tank and does not need to open the dome although it can be done if necessary for other reasons.

55 During the transportation period of the liquid in the tank there is no possibility of a leak through the outlet valve, because such valve is at such times above the liquid. The valve 9 at the bottom of the tank is not the outlet valve, it is a cleanout valve for convenience at the time the tank is cleaned out 60 before it receives its load. The invention of locating the outlet valve above the liquid would be the same if valve 9 were omitted entirely and the pipe 8 made integral with the pipe fitting 2 or otherwise connected 65 thereto.

On account of the curvature of tank 1 practically the whole of the liquid can be taken out with the siphon effect. The hanging cylinder 24 can be adjusted as closely to the bottom of a tank 1 as practical or the 70 outlet pipe 2 may be located at the bottom of a depression 28 (Fig. 3) in tank 1 so that the bottom of cylinder 24 is slightly spaced from the bottom of such depression, and thus 75 all the liquid will be drained from the tank except a small amount between the edge of the cylinder 24 and the bottom of the depression.

In addition to the other advantages in 80 locating the outlet valve above the liquid in the tank, there is an advantage with regard to keeping such valve usable. When it is in the bottom of the tank (as in the usual construction) dirt, sticks and even pieces of metal may be in the liquid to clog the valve and particularly to prevent it closing. When the outlet valve is opened to drain only a part of the tank in the old constructions, it has frequently been found impossible to close it and the liquid has continued to drain in spite of anything that could be done in those old constructions. In this invention, the siphon effect once started can be stopped by simply closing the valve 11 so as to again let the liquid subside to a level below the valve. Furthermore, the foreign articles in the liquid will usually settle with the sediment at the bottom of the tank and never be carried up the hanging cylinder 24 90 to reach the outlet valve. If any unforeseen 100 thing did cause valve 11 to stick either open or closed it is possible to get at it from the top through the dome while the liquid is yet in the tank. The cylinder 24 could be lifted to stop the siphon effect if pipe 8 is made integral or permanently fixed on pipe 2. Then again as shown in Fig. 2 the entire valve mechanism and associated parts for tank car 105 use can be lifted out of the dome, repaired 110 and replaced with great convenience.

115 It frequently happens that when a tank car is all connected for unloading and the outlet valve is wide open, a switch engine or other railroad car accidentally bumps into or sufficiently jars the unloading tank car so that its outlet connection is broken. To avoid the usual result when this happens, I provide a weakened point 30 around the pipe section 2 extending from the bottom of the car. If then this section breaks it will break 120 at 30 in the plane of the connection between pipe section 4 and the valve rod or pipe 7. The break will remove pipe 4 from supporting position under pipe 7. The spring 13 125 will immediately close valve 11. The check valve 18 will prevent any exit through pipe 7. Therefore, in time of accident the outlet from the tank is immediately closed and the contents of the car is safeguarded. This 130 is quite important for experience has shown 135

that the total contents of tank cars have been lost where a device of this character would save them.

Under the ordinary conditions of tank transportation of oils and other liquids, this invention serves to safeguard the contents in an effective way. When the tank is to be emptied in whole or in part, the invention safeguards the operation in that it is more nearly foolproof than the old constructions. The advantages mentioned are only some of those which can be found in actual use.

What I claim is:

1. A tank car for transporting liquids, having a main chamber for its liquid and a much smaller supplementary chamber for obtaining a difference in pressures above the liquids in such chambers, an outlet pipe for the tank car with an inlet located above the liquid in said supplementary chamber, a valve for the outlet pipe at the top thereof, communicating means between said chambers above the normal liquid level therein and means operable from without the main chamber for closing and opening said communication and simultaneously operating said valve, all constructed and arranged so that liquid in said tank car may flow from the bottom of one chamber to the bottom of the other chamber and be emptied from the top of the supplementary chamber when the pressure therein is less than that of the main chamber.

2. A tank car for transporting liquids, having a main tank for the liquid, a vertically arranged siphon apparatus in the tank provided with a conduit for liquid from the bottom of the tank to a point above the normal liquid level in the tank and another conduit from such point to and through the bottom of the tank, a valve at the top of the last named conduit, said conduits and valve being located wholly within the tank except for the outlet through the bottom thereof, means to establish a difference in pressure between the space above the liquid in the tank and the space surrounding the valve in said conduit and means to control said valve operable from without the tank.

3. A tank car for transporting liquids, having a main tank for the liquid, an outlet below the dome in the bottom of said tank, a pipe in said outlet extending to a point above the normal liquid level in the

tank, a valve at the top of said pipe, means to operate said valve from without the tank, a hood depending over said pipe to a point close to the bottom of the tank and means operable from without the tank to establish a lower pressure in the top of said hood than in the space above the liquid in the tank.

4. A tank car for transporting liquids, having a main tank for the liquid, an outlet below the dome in the bottom of the tank, a pipe in said outlet extending to a point above the normal liquid level in the tank, a valve at the top of said pipe, a hollow vertical valve rod extending downwardly to a point outside the tank, a valve nozzle at the upper end of said rod above the first mentioned valve, a hood and means to suspend it over said pipe and valve with its lower edge spaced from the bottom of the tank, a central opening provided in the top of said hood in line with said valve nozzle, said opening communicating with the space above the liquid in the tank outside of said hood.

5. A tank car for transporting liquids, having a main tank and dome, an outlet conduit extending from the bottom of the tank and opening into the dome space above the liquid, a valve for such opening, and apparatus controlled from without the tank to operate said valve and to force the liquid by siphonic effect through said valved opening.

6. A tank car for transporting liquid, having a main tank, an outlet conduit in the tank with its inlet opening above the normal liquid level in the tank, a valve in said opening and apparatus controlled from without the tank to operate said valve and force the liquid up to said opening for discharging operations.

7. A tank car for transporting liquid, an outlet conduit in the tank, extending through the bottom thereof and with its opening above the normal liquid level in the tank, means controlled from without the tank to cause the liquid to flow out through said conduit said means having a weakened line of cleavage to render said means inoperative when broken by movement of the car while unloading.

In testimony whereof I have affixed my signature.

RUDOLPH WELCKER.
